UNITED STATES PATENT OFFICE.

J. C. HAWKINS, OF NEWTON, IOWA.

PAPER-FASTENER.

1,130,595.

Specification of Letters Patent.

Patented Mar. 2, 1915.

Application filed November 6, 1911. Serial No. 658,635.

To all whom it may concern:

Be it known that I, J. C. HAWKINS, a citizen of the United States, residing at Newton, county of Jasper, and State of Iowa, have invented a certain new and useful Paper-Fastener, of which the following is a specification.

My invention relates to paper fasteners and has for its object an improvement in that class of fasteners which by a single operation cut a tongue out of the sheets of paper to be fastened together and at the same time slit the sheets near the base of the tongue, the latter being automatically drawn through the slit in the sheets. In devices of this kind heretofore constructed, the slitting knife and the folding member were made of a single piece of steel, the folding member having a set which normally tended to hold the free end thereof in the eye of the slitting knife. This necessitated the provision of means for normally keeping the free end of the folding member away from the eye in the knife. When the device was not in use the folding member was thus subjected to a tension at the base thereof, with the result that the member would break off after a comparatively short life. To remedy this defect I have provided a fastener in which the folding member is separate from the slitting knife and normally rests in a position away from the eye in the knife. During the operation of the device the free end of the folding member is automatically brought toward the eye in the knife. In its normal position the folding member is not subjected to any strain, and it will therefore last considerably longer than the folding member of the devices heretofore constructed, as above noted.

Viewed in another respect, my invention comprises features of novelty in paper fasteners of the above-named class having a pair of spring-pressed jaws which are operated by handles. One of these features consisting in arranging the springs inside of the jaws.

Another feature consists in providing the upper jaw with means for positively forcing the spring plate between the jaws upwardly when the jaws are separated, while the lower jaw has means for limiting the upward movement of the spring plate.

In the accompanying drawings: Figure

1 is a side view of a fastener embodying my invention; Fig. 2 is a cross-sectional side view showing the parts in their normal position, the handles being broken away; Fig. 3 is a view similar to Fig. 2 showing the jaws in their closed position; Fig. 4 is a fragmentary cross-sectional view showing a modified form of my invention with respect to the folding member, the jaws being in open position; Fig. 5 is a view similar to Fig. 4, the jaws being in closed position; Fig. 6 is a fragmentary cross-sectional view showing a second modified form of my invention with respect to the folding member, the jaws being in open position; Fig. 7 is a view similar to Fig. 6, the jaws being in closed position; Fig. 8 is a top plan view of the spring plate between the jaws and with which the cutting mechanism cooperates to cut the paper; Fig. 9 is a fragmentary view of the paper showing how the integral tongue passes through the slit to fasten the sheets together; Fig. 10 is a cross-sectional view on line 10—10 of Fig. 9; Fig. 11 is a longitudinal cross-sectional view of a modified construction, the jaws being in open position; and Fig. 12, is a view of Fig. 11 with the jaws in closed position.

I will first take up the detailed description of the forms shown in Figs. 1, 2, 3, 11 and 12. The operating handles 1 and 2 are pivoted together at 3. The gripping, or outer portions, of these handles are preferably rounded off, while the inner portions are bifurcated. The bifurcations of the handle 1 are indicated at 4 and 5, while the bifurcations of the handle 2 are indicated at 6 and 7. Between the bifurcations 4 and 5 is pivoted the lower jaw 8 by means of the bolt or rivet 9. The upper jaw 10 is pivoted near the outer end of bifurcations 6 and 7 of the handle 2 by means of the bolt or rivet 11. The inner end of the lower jaw 8 is provided with a longitudinal slot 12 in which engages the transverse stud 13 carried by the handle 2 at the base of the bifurcations. The upper jaw 10 is at its rear end provided with a longitudinal slot 14 in which engages the transverse stud 15 carried by the handle 1 in alignment with the stud 13 on the other handle. It will be apparent that the above-described connections between the jaws and the handles cause the jaws to maintain a position of parallelism.

at all times. Fig. 3 shows the jaws in their closed position. It will be seen that in this position of the jaws the studs 13 and 15 are at the open end of the associated slots 12 and 14, whereas in the normal position of the parts the studs are at the bases of the slots, as shown in Figs. 1 and 2. In Figs. 1, 2 and 3 the jaws are normally maintained in an open position by means of the 10 springs *a* and *b* housed within the jaws. The spring *a* in the upper jaw is at its rear end connected to the transverse stud 15 of the handle 1 and its forward end connected to the bolt or rivet 11. The spring *b* in the 15 lower jaw is at its rear end connected to the slotted link *c* which terminates in an eye *d* for receiving the stud 13. The forward end of the spring *b* is connected to the bolt 31 which is secured vertically in the lower jaw 20 and at its upper end projects beyond the jaw for a purpose to be presently described. It will thus be seen that the rear ends of the springs are connected to the handles and the front ends to the jaws, with the result 25 that the springs normally maintain the jaws and handles in open position, as shown in Figs. 1 and 2. I will at this point call attention to the arrangement of the springs in the construction of Figs. 11 and 12. In 30 this form the springs are arranged in the gripping portions of the handles. The spring *a'* is at its rear end attached to the handle 1 at the point 1^a and at its forward end to the extension 10^a of the upper jaw 35 10. The spring *b'* is at its rear end attached to the handle 2 at the point 2^b and its forward end to the extension 8^b of the lower jaw 8.

In the various forms of my invention the 40 wedge-shaped cutting knife 16 is securely mounted in the upper jaw 10, the front edge of the knife resting against the transverse stud 17, while the rear extensions 18 rest against the slitting knife 19. In Figs. 1, 45 2, 3, 4, 5, 11, and 12, the slitting knife abuts against the transverse lug 20 secured in the jaw 10. It will thus be seen that the two knives which comprise the cutting mechanism are firmly held in the upper jaw 10 50 between the studs 17 and 20. However, any suitable means may be employed for rigidly mounting the knives on the jaw 10. The slitting knife 19 is provided with an eye 21 near its cutting end. In Figs. 1, 2, 3, 11 55 and 12, the slitting knife 19 is at its inner end provided with a slot or opening 22. Associated with the cutting mechanism is the folding member or folder, as it will be hereinafter called, indicated as a whole by 60 the reference numeral 24 in Figs. 1, 2, 3, 11 and 12. In the form shown in these figures the folder consists of a downwardly extending section 25 and a longitudinal section 26 substantially parallel with the jaw 10, being 65 made of an inelastic metal thereby having

a substantially rigid form. The longitudinal section 26 is provided with side extensions 27 having elongated slots 27^a through which passes the stud 15. The slot or opening 22 at the base of the knife is to accommodate the longitudinal section 26 of the folder and to hold the same in an open position substantially parallel with the jaw. The curved free end 28 of the folder 24 terminates substantially in alignment with 75 the eye 21 in the slitting knife, and normally rests in a position away from said eye, as indicated in Figs. 2 and 11.

The lower jaw 8 has secured thereto the die or base-plate 29 and the spring-plate 32. 80 These are held in place by a bolt 30 which passes through the slot in the link *c* and also passes through an elongated hole in the die-plate, 29 and carries a nut 33. The rear ends of these plates 29 and 32 are connected 85 by a screw 30^a which is reduced in cross section just back of the head so that it will enter a slot in the down-turned extension 32^a of plate 32, and so be free to turn without advancing forwardly or backwardly 90 with respect to that plate, but its threaded end takes into the down-turned extension 29^a of the die or base-plate 29. By turning the screw 30^a in or out, the die-plate 29 may be shifted slightly with respect to the lower 95 jaw, thereby changing its position with respect to the cutter 16 to tighten or loosen the shearing action when the paper is cut. The set of the plate 32 is such that in an unrestrained condition it rests against the 100 lower plate 29. When the parts are in normal position as indicated in Figs. 1 and 2, the plates are held apart by reason of the fact that the lateral projections 34 of the plate 32 rest upon the engaging surfaces 35 105 of the bifurcations 4 and 5.

Fig. 8 shows the lateral projections on the plate 32 and Fig. 1 shows how these projections rest on the engaging surfaces 35. 110 When the handles are brought together to close the jaws the engaging surfaces 35 move below the lower plate 29, as shown in Fig. 3, and the upper plate 32 is by reason of its inherent resiliency free to move toward the lower plate 29. The screw or bolt 31 is provided with a head 36 against which the plate 32 abuts when the handles are allowed to spread.

In Figs. 11 and 12 the engaging surfaces on the bifurcations of the handles are dispensed with and the spring plate is forced upwardly by the bolt 10^b which is at its outer end rigidly secured to the upper jaw 10. Section 26 is slotted at 26^a to allow freedom of movement with respect to bolt 10^b. The lower or inner end of the bolt 10^b projects through an opening in the plate 32 and is provided with a head 10^c which engages the under face of the plate and draws the same upward when the handles are sep- 120 125 130

arated. A lug 29^a struck up from the lower plate 29 passes through a slot 32^b in the plate 32 and has an extension 29^b which overlaps the plate 32 to limit the upward movement thereof as clearly shown in Fig. 5. The bolt head 10^c passes through the opening 29^c when the handles are pressed together. The upper plate 32 is provided with a wedge-shaped opening 37 in alinement with the wedge-shaped cutting knife 16 and with an opening 38 in alinement with the slitting knife 19. The lower plate 29 is provided with an opening 39, the edges of which coöperate with the knives 16 and 15 19 to cut a tongue and a slit in the paper. In other words the plate 29 acts as the female member of the die, of which the cutting mechanism is the male member. To prevent the free end of the folder 24 from accidentally striking against the edge of the opening 37, whereby the folder might become bent or broken, the spring plate 32 is provided with an inclined guide lug 32^c which directs the folder through the opening 37 without any danger of injury to the folder.

The operation of the fastener will now be clear from the above detailed description and is as follows: The sheets of paper which it is desired to fasten together are inserted in the opening between the plates 29 and 32 and the handles are pressed together to close the jaws. During the movement of the jaws toward each other, the wedge-shaped knife 16 cuts a tongue out of the paper while the slitting knife 19 slits the paper near the base of the tongue. Since the folder 24 is rigidly connected with the handle 1 at 15, the bringing together of the handles will 30 draw the folder rearwardly with respect to the jaws until the free end of the folder rests substantially in the eye 21 of the slitting knife 19, as indicated in Figs. 3 and 12. During this movement of the folder relative 35 to the jaws, it will bend or fold the cut-out tongue 40 through the eye in the knife, so that upon the separation of the jaws the tongue will be drawn through the slit 41 in the paper 41^a, as indicated in Figs. 9 and 40 10. The bodily shifting of the folder 24 with respect to the jaws, does not occur immediately upon forcing the jaws toward each other, but is delayed until the stud 15 reaches the rear end of the elongated slots 55 27^a. The purpose of this lost-motion connection between the folder and the handles is to close the jaws sufficiently to bring the free end 28 of the folder beyond the opening 37 before the rearward shifting of the folder 60 into operative position takes place. A single operation of the device is sufficient to automatically cut a tongue out of the paper, slit the paper near the base of the tongue, and draw the free end of the tongue through 65 the slit. By arranging the folder as above

described, it will be apparent that the folder is at no time subjected to any substantial degree of tension and is simply shifted bodily against the slitting knife during the operation of the device. This obviates the liability of breakage which is so apt to occur where the folder is a spring blade, having a normal set toward the eye of the knife, and where it is consequently necessary to hold the spring away from the knife in opposition to its normal set.

In the modification of folder shown in Figs. 4 and 5, the folder 24^a is a spring strip secured at one end to the stud 42, which is carried by the jaw 10. The normal position of the folder is as indicated in Fig. 4. When the jaws are closed, the lug 43 which is struck-up on the jaw 8 engages the curved portion of the folder and forces the free end thereof into the eye of the slitting knife 19, as indicated in Fig. 5. When the jaws are opened again the normal set of the folder will cause the same to assume the position indicated in Fig. 4.

Another modified form of folder is illustrated in Figs. 6 and 7 in which the folder 24^b is pivoted at an intermediate point to the rotatable stud 44 carried by the jaw 10. A compression spring 45 is fixed at one end to the jaw 10 and at the other end to the rear of the folder 24^b to normally hold the same in the position indicated in Fig. 6. In other words, the compression spring normally tends to hold the rear end of the folder in a downward position so that the free end of the folder is held away from the eye of the cutting knife 19. When the jaws are closed, the projecting end 31^b of the bolt 31^a will strike the folder and move the rear end of the same upwardly, whereby the free end of the folder is moved into the eye of the slitting knife, as shown in Fig. 7. When the jaws are again separated the spring 45 restores the folder to the position indicated in Fig. 6.

In describing the modifications shown in Figs. 4 to 7 inclusive, I have not thought it necessary to describe in detail those parts which have already been described in connection with the constructions shown in Figs. 1, 2, 3, 11, and 12, since such detailed description would be mere repetition.

While I have described and illustrated certain specific forms of my invention, I would have it understood that I do not intend to be limited to those forms, since it is obvious that changes and modifications will occur to those skilled in the art without departing from the scope of the invention as defined in the appended claims.

In my co-pending application, Ser. No. 652,957, filed October 5th, 1911, claims are made on the paper fastening machine having a pivoted tucker.

Having thus described my invention, what

I claim as new and desire to secure by Letters Patent of the United States is:

1. In a paper fastener, the combination of a cutting knife to form a tongue from the paper, a slitting knife movable to slit the paper near the base of the tongue, said slitting knife being provided with an eye near its slitting edge, and a substantially inelastic folder separate from said knives and movable bodily to force the end of the tongue into the eye of the slitting knife whereby the slitting knife upon its return movement will draw the end of the tongue through the slit in the paper.
2. In a paper fastener, the combination of a cutting knife to form a tongue from the paper, a slitting knife to slit the paper near the base of said tongue, said slitting knife being provided with an eye near its slitting edge, a slidably mounted folder separated from said knives and normally having its free end away from the eye of the slitting knife, and means for sliding said folder with a positive movement to bend said tongue through said eye, whereby the slitting knife automatically draws the end of the tongue through the slit when said knife is withdrawn.
3. In a paper-fastener, the combination of a cutting knife to form a tongue from the paper, a slitting knife to slit the paper near the base of said tongue, said slitting knife being provided with an eye near its slitting edge, a folder separate from said knives and normally having its free end away from the eye of the slitting knife, and means for bodily shifting said folder toward said slitting knife to cause the free end of said folder to bend the tongue through said eye, whereby the slitting knife automatically draws the end of said tongue through the slit when the knife is withdrawn.
4. In a paper-fastener, the combination of a pair of jaws, a cutting knife to form a tongue from the paper, a slitting knife to slit the paper near the base of the tongue, said knives being rigidly mounted in one of said jaws, a slidably mounted folder associated with said knives for causing the slitting knife to draw the end of the tongue through the slit in the paper when the jaws are opened, said folder being separate from said slitting knife, and means for closing and opening said jaws.
5. In a paper-fastener, the combination of a pair of jaws, a cutting knife to form a tongue from the paper, a slitting knife to slit the paper near the base of the tongue, said slitting knife having an eye, said knives being rigidly mounted in one of said jaws, a folder associated with said knives, said folder comprising a portion extending between said knives and a portion extending longitudinally in the jaw which carries the knives, a pair of pivotally connected gripping members for closing and opening said jaws, and means for bodily shifting said folder toward said slitting knife to cause the free end of said folder to bend the tongue through said eye and causes the slitting knife to draw the tongue through the slit when the jaws are opened.
6. In a paper-fastener, the combination of a pair of jaws, a cutting knife to form a tongue from the paper, a slitting knife to slit the paper near the base of the tongue, said slitting knife having an eye, said knives being rigidly mounted in one of said jaws, a folder associated with said knives, a pair of pivotally connected gripping members for closing and opening said jaws, and means for connecting said folder with one of said gripping members for bodily shifting the folder relative to said jaws when the latter are closed, whereby the free end of the folder bends the tongue through said eye and causes the slitting knife to draw the tongue through the slit when the jaws are opened.
7. In a paper-fastener, the combination of a pair of jaws, a cutting knife to form a tongue from the paper, a slitting knife to slit the paper near the base of the tongue, said slitting knife having an eye, said knives being rigidly mounted in one of said jaws, a folder associated with said knives, said folder comprising a portion extending between said knives and a portion extending longitudinally in the jaw which carries the knives, a pair of pivotally connected gripping members for closing and opening said jaws, and means whereby the operation of the gripping members to close the jaws produces bodily shifting of the folder so that the free end of the folder bends the tongue through said eye and causes the slitting knife to draw the tongue through the slit when the jaws are opened.
8. In a paper-fastener, the combination of a cutting knife to form a tongue from the paper, a slitting knife to slit the paper near the base of said tongue, said slitting knife being provided with an eye near its slitting edge, a folder separate from said slitting knife and normally having its free end away from the eye of the slitting knife, and means for bodily shifting said folder toward said slitting knife to cause the free end of said folder to bend the tongue through said eye, whereby the slitting knife automatically draws the end of said tongue through the slit when the knife is withdrawn, and a lug for guiding said folder into folding position.
9. In a paper-fastener, the combination of a pair of jaws, a cutting knife to form a tongue from the paper, a slitting knife to

- slit the paper near the base of the tongue, said slitting knife having an eye, said knives being rigidly mounted in one of said jaws, a folder associated with said knives, 5 said folder comprising a portion extending between said knives and a portion extending longitudinally in the jaw which carries the knives, a pair of pivotally connected gripping members for closing and opening said 10 jaws, and a lost-motion connection between the inner end of said folder and one of said gripping members for bodily shifting the folder relatively to said jaws into folding position after the latter have been brought 15 together a certain amount, whereby the free end of the folder bends the tongue through said eye and causes the slitting knife to draw the tongue through the slit when the jaws are opened.
- 20 10. In a paper fastener, the combination of a pair of jaws, handle members for closing said jaws, a spring housed in each of said jaws and connected at its forward end to the jaw and at its rear end to one of the 25 handle members for normally holding the jaws in open position, a cutting knife and a slitting knife carried by one of said jaws, and a folder associated with said knives for causing the slitting knife to draw the end 30 of the tongue through the slit in the paper when the jaws are opened.
11. In a paper fastener, the combination of a pair of jaws, handle members for operating said jaws, a cutting knife and a slitting knife carried by one of said jaws, a 35 folder associated with said knives for causing the slitting knife to draw the end of the tongue through the slit in the paper when the jaws are opened, a resilient plate secured to the other jaw and having a normal set toward said jaw, engaging means 40 secured to said first mentioned jaw for holding said plate away from said other jaw,
- and means carried on said other jaw for positively limiting the outward movement 45 of said plate.
12. In a paper fastener, the combination of a pair of jaws, handle members for operating said jaws, a cutting knife and a slitting knife carried by the upper jaw, a 50 folder associated with said knives for causing the slitting knife to draw a paper tongue through the slit in the paper when the jaws are opened, a stripper plate secured to the lower jaw and having a normal set toward that body, and means secured to said upper jaw at the rear of said 55 slitting knife for lifting the stripper plate from the lower jaw when the fastener is opened. 60
13. In a paper fastener, the combination of a pair of parallel movement jaws, handle members for operating said jaws, a tongue cutting knife and a slitting knife carried by the upper jaw, said slitting knife having an eye, a folder associated with said knife for pressing the cut tongue through the eye of the slitting knife so that the tongue may be drawn through the slit in the paper when the jaws are opened, a stripper plate secured to the lower jaw, and means extending downward from the upper jaw at the rear of the slitting knife to engage said stripper plate and lift it when the jaws are opened, and means for positively limiting 75 the upward movement of said stripper plate to clear the knives of paper when the jaws are opened. 70

In witness whereof, I hereunto subscribe my name to this specification in the presence 80 of two witnesses.

J. C. HAWKINS.
